RESILIENT BRUSH AND BUFFER HOLDING
HANDLE

Robert S. Parker, Dover, N. J.

Application June 21, 1950, Serial No. 169,385

3 Claims. (Cl. 15—114)

1

This invention relates to a device for holding a shoe brush and a shoe buffer as a unit, so that they both may be used at the same time.

The object of the invention is to provide a shoe brush and shoe buffer holder which will simplify and facilitate the task of shining a pair of shoes.

Another object of the invention is to provide a device for holding a shoe brush and a shoe buffer as a unit, so that the two articles can be used at one time, instead of first using the shoe brush and then putting the brush down and in turn picking up the buffer.

A further object of the invention is to provide a shoe brush and shoe buffer holder which is extremely simple and inexpensive to manufacture.

Other objects and advantages of the invention will be apparent during the course of the following description.

In the accompanying drawings forming a part of this application, and in which like numerals are used to designate like parts throughout the same:

Figure 1 is a top plan view, showing the position of the holder of the present invention when holding a shoe brush and a shoe buffer as a unit, the brush and buffer being shown in broken lines;

Figure 2 is a side elevational view of the assembly shown in Figure 1;

Figure 3 is an end elevational view of the assembly as shown in Figures 1 and 2;

Figure 4 is an end elevational view of the holder illustrating the spring action of the arms when the holder is detached from the brush and buffer.

Referring in detail to the drawings, the numeral 10 designates a conventional shoe brush, while the numeral 11 designates a conventional shoe buffer (broken lines, Figures 1, 2 and 3). The present invention is directed to a device for holding the brush 10 and buffer 11 in side-by-side relation as a unit, so that these two articles can be used at the same time for shining a pair of shoes.

The holder of the present invention includes a pair of spaced, parallel, spring clamps 12 which are preferably made of spring metal. Each of the clamps 12 has the same construction, each clamp including a pair of spring arms 14 and 15 that are connected by a loop 16, the arms 14 and 15 being urged together, due to the resiliency inherent in the material of which the arms are made.

Secured to the free end of each of the spring

2

arms 14 and 15 is a pad 17, and the pads 17 are adapted to abut and engage the sides of the shoe brush 10 and the shoe buffer 11.

The holder of the present invention further includes a retaining member 18 which may be fabricated of any gauge wire. The retaining member 18 includes an intermediate handle portion 19 which is adapted to be gripped in the user's hand when the shoes are being shined. The handle portion 19 is constructed by bending the intermediate portion of the retaining member in a zig-zag manner, as best seen in Figure 1.

Portions of the retaining member 18 project through the loop 16 of the clamps 12, and the retaining member 18 terminates in a pair of spaced, parallel legs 20 and 21. Secured to the free end of each of the legs 20 and 21 is a cushion 22, the pair of cushions 22 being interposed or positioned between the shoe brush 10 and the shoe buffer 11.

From the foregoing, it is apparent that a device has been provided whereby a shoe brush, such as the shoe brush 10, and a shoe buffer 11 can be held together as a unit, so that they both may be used at the same time. The advantage of the holder is that it will not be necessary to first use the brush 10 and then put the brush down and pick up the buffer 11, since the whole procedure is simplified by using the shoe brush 10 and buffer 11 together. By means of the holder of the present invention, the time required to shine a pair of shoes is greatly reduced.

The pads 17 may be fabricated of any suitable material, such as rubber, and these pads 17 engage the brush 10 and buffer 11 and due to the spring action or resiliency of the clamps 12, the brush and buffer will be held together as a unit. Also, the pair of cushions 22 on the lower ends of the legs 20 and 21 are positioned between the brush and the buffer and serve to insure that the brush and buffer will not be placed too close to each other. Furthermore, it will be seen that when the arms 14 and 15 of the clamp 12 are extended or are under spring tension, as when both brushes are in place in the holder, the retaining member 18 will be held firmly or immobile by the two loops 16, because these loops 16 are reduced in size when the arms 14 and 15 are extended outwardly. Thus, in this way the complete unit becomes rigid, and there is no possibility for any part of the holder to get out of position. Also, the plane of the handle portion 19 is parallel to the plane formed by the tops

55

of the brush and buffer so as to provide the user with a better grip on the holder.

When the holder is detached from the brush 10 and buffer 11, as when these articles are not being used, the parts of the holder will assume the position shown in Figure 4, due to the spring action of the clamps, so that the holder will occupy a minimum amount of space.

I claim:

1. A device for holding a shoe brush and a shoe buffer together as a unit comprising a pair of spring clamps, each of said clamps comprising a pair of arms mounted for movement toward and away from each other and interconnected together by a loop, a retaining member extending 10 through said loops and including an intermediate handle portion, a pair of spaced, parallel legs extending from said retaining member and terminating between said brush and buffer, and a cushion arranged on the free end of each of said 15 legs and a pad arranged on the free end of each of said arms.

2. In a shoe brush and buffer holder, the combination which comprises an inverted U-shaped retaining member having an intermediate section providing a handle and having depending legs with cushions on the lower ends extended from each end, and a pair of spring arms mounted on each end of the intermediate section of the retaining member and extended downwardly in the free positions, said spring arms having gripping pads on the lower ends and the lower ends of said arms being urged inwardly by resiliency inherent therein whereby the pads on the arms 20 coact with said cushions of the depending legs 25

for gripping a brush in one side of the holder and a buffer on the opposite side of the holder.

3. In a shoe brush and buffer holder, the combination which comprises an inverted U-shaped retaining member having an intermediate section providing a handle and having depending legs with cushions on the lower ends extended from each end, and a pair of spring arms mounted on each end of the intermediate section of the retaining member and extended downwardly in the free positions, said spring arms having gripping pads on the lower ends and the lower ends of said arms being urged inwardly by resiliency inherent therein whereby the pads on the arms coact with said cushions of the depending legs for gripping a brush in one side of the holder and a buffer on the opposite side of the holder, said intermediate section of the retaining member having corrugations therein to facilitate gripping and said spring arms having ends extended toward said cushions with the arms extended for gripping a brush and buffer and said pads being positioned on the extended ends.

ROBERT S. PARKER.
